Attn:

UNITED STATES PATENT OFFICE.

MALCOLM CAMPBELL, OF WOONSOCKET, RHODE ISLAND.

DESIGN FOR A BOLSTER-RAIL.

SPECIFICATION forming part of Design No. 23,554, dated August 7, 1894.

Application filed July 2, 1894. Serial No. 516,382. Term of patent 14 years.

To all whom it may concern:

Be it known that I, MALCOLM CAMPBELL, a citizen of the United States, residing at Woonsocket, in the county of Providence and State of Rhode Island, have invented and produced a new and original Design for Bolster-Rails, of which the following is a specification, reference being had to the accompanying drawing, forming a part of this specification, in which the same symbol is used to designate the same part wherever it occurs.

In the drawing the figure is a perspective view of my design for a bolster-rail.

The leading feature of my design consists in a bolster-rail having a base provided with flanges and a channel, and is generally the shape and contour of an I-shaped rail or beam provided with a continuous base as shown. The rail, *a*, is composed of the web, provided

at its ends with laterally extending ribs or flanges, *b c*. Below the flange, *c*, the rail is provided with laterally extending flanges or ribs, *e*, which extend out beyond the ribs, *b c*, as shown in the drawing. The rail is cored or grooved out in its base at *f*. It is also provided with apertures as shown.

What I claim is—

The design for a bolster rail substantially as herein shown and described.

In testimony whereof I have signed my name to this specification, in the presence of two subscribing witnesses, this 29th day of June, A. D. 1894.

MALCOLM CAMPBELL.
